ARTICLE CARRIER

Edwin L. Arneson, Morris, Ill., assignor to Morris Paper Mills, Chicago, Ill., a corporation of Illinois

Application August 4, 1951, Serial No. 240,320

6 Claims. (Cl. 229—28)

1

The present invention relates to improvements in a flexible paperboard carrier for bottles and other articles of like size and shape. More particularly, the invention bears on a partitioned or cellular carrier featuring a longitudinal and cross partition structure of improved character.

It is an object of the invention to provide an article carrier of the foregoing general description, characterized by opposed pairs of side and end walls, a multi-ply longitudinal suspending and partition panel disposed medially between and parallel to the side walls, and a cross partition structure of improved sort constituted by a set of panel elements hingedly articulated to one another in longitudinally extending order, and a further set of partition panel elements which are hingedly joined to one of the panel elements of said series in a transversely extending order.

A further object of the invention is to provide a simple paperboard article carrier of the type, described comprising a multi-ply longitudinal partition and suspending member having a pair of cross partition panel elements integrally hinged thereto on a vertically extending fold line, terminating at the lower margin of two of the plies of the partition member, which panel elements are otherwise freed from the partition to enable their swinging to a right angle to the latter, and further sets of cross partition panel elements integrally hinged to the same respective plies of the longitudinal partition member on fold lines coinciding with the bottom margin thereof, one of the panel elements of each set being integrally hinged to another for folding into juxtaposed, face contacting and adhesively secured relation thereto, the integrally hinged panel elements being adapted to extend between the cross partition member and a side wall of the carrier, being adhesively secured to the respective side walls to subdivide the space on one side of the longitudinal partition member into bottle receiving cells.

A still further object is to provide an article carrier of the sort referred to in the preceding paragraph in which the transversely extending cross partition panel elements are substantially coextensive in height with the side walls of the carrier, thereby affording full depth protection for bottles disposed in the cells defined by the elements.

Yet another object is to provide a flexible paperboard blank for an improved article carrier of the above description.

The foregoing statements are indicative in a general way of the nature of the invention.

2

Other and more specific objects will be apparent to those skilled in the art upon a full understanding of the construction and operation of the device.

A single embodiment of the invention is presented herein for purpose of illustration, and it will be appreciated that the invention may be incorporated in other modified forms coming equally within the scope of the appended claims.

In the drawings:

Fig. 1 is a top plan view of a flexible paperboard blank employed in the manufacture of the improved carrier;

Fig. 1A is a fragmentary plan view illustrating a portion of the blank of Fig. 1 following preliminary gluing and folding operations;

Fig. 2 is a plan view, partially broken away, showing the carrier after another operation in the manufacture thereof;

Fig. 2A is a fragmentary plan view showing the carrier following yet another step in the manufacture thereof;

Fig. 3 is a plan view of the carrier in its completed, knock-down condition;

Fig. 4 is a side elevational view of the carrier in completed and erected condition;

Fig. 5 is a view in horizontal section along a line corresponding to line 5—5 of Fig. 4, further illustrating details of structure and the relationship of the carrier parts; and

Fig. 6 is a view in transverse vertical section along a line corresponding to line 6—6 of Fig. 5.

Referring to Fig. 1 of the drawings, the reference numeral 10 generally designates a flexible paperboard blank from which the improved bottle carrier is fabricated. This blank is symmetrical about a medial, longitudinally extending line 11, except for a bottom forming section 12 integrally attached to one edge of the blank. Accordingly, only the parts on one side of the medial line 11 will be described, on the understanding that similar parts and relationships of parts that are on opposite sides of the line are designated by similar reference numerals.

Blank 10 includes rectangular side wall panels 12 defined by parallel creases 13, 14, and the bottom forming section is hingedly joined by a crease 15 to one side of one of the side wall panels 12.

50 A medial crease 16 subdivides the bottom section into two like portions, and a glue lap is hinged by a further crease 17 onto the outermost portion, the glue lap being designated 18.

The crease 14 hinges an edge wall panel 19 to one end of side wall panel 12, and a longitudinal

3

partition forming panel or flap 20 is conjoined to end wall panel 19 by the crease 21.

The opposite end of side wall panel 12 has an end wall panel 22 integrally hinged thereto by the crease 13. End wall panel in turn has hinged thereto, by means of a transversely extending crease 23, the partition forming unit 24 with which the provisions of the present invention are primarily concerned. Crease 23 extends the entire width of the blank 10 and a handle panel 25 is integrally hinged to the unit 24 by the crease 23. Panel 25 is freed for movement relative to side and end wall panels 12, 22 by means of a shaped slit 26. The panel 25 is provided with hand holes 27 of well known type, and the respective panels 25 are integrally hinged to one another by a longitudinally extending crease 28 at medial line 11 of the blank. Similarly, the partition units 24 are integrally hinged together by an extension of crease 28 which is designated 28', the left hand end of this crease extension terminating in an elongated, longitudinally extending slot 29 to facilitate bending of the material of the blank in this zone. At the opposite end of the blank, the longitudinal partition flaps 20 are integrally hinged to one another by a relatively short crease 30 which, along with creases 28, 28' and slot 29, coincide with the medial line 11, and with the top of the top margin of the suspending member of the carrier in the completed condition of the latter.

As indicated above, the invention primarily deals with the manner in which a longitudinal and cross partition structure to subdivide the interior of the carrier into equal sized cells is provided by the units 24. To this end, each unit is cut inwardly from its left hand edge by means of a slit 31 which is located about midway of the vertical dimension of a main, longitudinal partition panel 32 of unit 24. A crease 33 at 90° to slit 31 defines a partition panel element 34 which is freed from panel 32 for bending at a right angle thereto. Panel element 34 carries a narrow glue lap 35, hinged thereto by crease 34'.

A second cross partition defining unit includes a panel 36 integrally hinged to the bottom margin of longitudinal partition panel 32 by means of a crease 37. Panel member 36 in turn has a cross partition panel element 38 integrally hinged thereto by crease 39, the element 38 being separated from the partition panel 32 by means of a slit 40 coinciding with the bottom margin of the latter. It is thus seen that the last described unit is swingable about crease 37 into face-to-face relation to panel 32, its panel element 38 being then swingable about crease 39 into right angular relation to panel 32, while panel element 34 is similarly swingable about crease 34' to a like relationship. Member 38 carries a narrow glue lap 41 integrally hinged thereto by a crease 42. Like panel 25, the longitudinal partition panel 32 is provided with hand hold openings 43 of a well known type.

In completing the carrier from the blank illustrated in Fig. 1, the unit including panel 36 and attached cross partition panel element 38 are first swung upwardly, inwardly and downwardly about crease 37 and adhered by previously applied adhesive on member 36, indicated by stippling in Fig. 1, in face-to-face engagement with panel 32. This leaves the blank in the condition illustrated in Fig. 1A, in which it is seen that the glue lap 41 of member 38 is lapped over

4

onto the body of the member 34. Next, adhesive is applied to the exposed surfaces of glue laps 35, 41, as well as to the portion of the longitudinal partition panel 32 above the slit 31, as indicated by stippling in Fig. 1A. The partition units 24 are then folded bodily upwardly, inwardly and downwardly about crease 23, causing the glue laps 35, 41 to be adhered to the side wall panel 12 in spaced relation to one another, and the panel 25 to adhere to panel 32 in the zone of the hand holes 27, 43. This leaves the blank in the condition shown in Fig. 2. Further adhesive is next applied to the exposed surface of the panel 32, as shown in stippling in Fig. 2, and the end wall panel 19 and its longitudinal partition flap 20 are then folded upwardly, inwardly, and downwardly about crease 14, causing the flap 20 to be adhered to the glued portion of panel 32 and leaving the blank in the condition shown in Fig. 2A. The article is completed by applying adhesive to the exposed surface of one of the panels 32 and partition flaps 20, shown stippled in Fig. 2A, also to the bottom section glue lap 18, and by successively folding the two sections of the blank onto one another above medial line 11, then the bottom section about its medial crease 16. This completes the carrier in its knock-down condition shown in Fig. 3.

Referring to Figs. 4, 5 and 6 of the drawings, it is seen that the invention provides a carrier having full depth bottle protection along its longitudinal medial partition 32, 20, also full depth protection at the transverse partition 35 which are constituted by panel elements 34 and 38. The latter are both integrally hinged to panel 32. The carrier is sturdy, is fabricated from a blank of minimum size, and is well adapted for production on existing gluing and folding machinery.

I claim:

1. An article carrier fabricated from flexible paperboard stock and comprising opposed pairs of side and end walls, a bottom extending between said side walls, a longitudinal partition disposed medially between said side walls and hinged to one of said end walls, said partition comprising a longitudinally extending panel having a cross partition element connected thereto on an integral vertical hinge located in inwardly spaced relation to an end thereof, which partition element is hingedly secured to a side wall, and a further cross partition unit integrally hinged to the bottom margin of the longitudinal partition panel, said further cross partition unit including a panel element folded upwardly about said bottom hinge to said longitudinal partition panel and disposed in face to face relation thereto, and a cross partition panel integrally hinged at one end by a vertical crease to said upwardly folded panel element and hingedly secured at its opposite end to said side wall, said last named cross partition panel being separated by a cut from said bottom margin of said longitudinal partition panel.

2. An article carrier fabricated from flexible paperboard stock and comprising opposed pairs of side and end walls, a bottom extending between said side walls, a longitudinal partition disposed medially between said side walls and hinged to one of said end walls, said partition extending downwardly substantially to the plane of the bottom margin of the walls, said partition comprising a longitudinally extending panel having a cross partition element connected there-

to on an integral vertical hinge located in inwardly spaced relation to an end thereof, which partition element is hingedly secured to a side wall, and a further cross partition unit integrally hinged to the bottom margin of the longitudinal partition panel, said further cross partition unit including a panel element folded upwardly about said bottom hinge to said longitudinal partition panel and disposed in face-to-face relation thereto, and a cross partition panel integrally hinged at one end by a vertical crease to said upwardly folded panel element and hingedly secured at its opposite end to said side wall, said last named cross partition panel being separated by a cut from said bottom margin of said longitudinal partition panel.

3. A flexible paperboard article carrier blank comprising hingedly connected side and end wall panels, a longitudinal partition panel integrally hinged by a transverse crease to an end of an end wall panel, a first cross partition element integrally hinged by a vertical crease to said partition panel, a panel element integrally hinged by a longitudinal crease to said longitudinal partition panel and adapted to be folded into side-by-side relation to the latter, and a second cross partition element integrally hinged by a transverse crease to an end margin of said panel element and separated by a cut from said longitudinal partition panel, said first and second cross partition panel elements being adapted to be hingedly secured to a side wall at the ends thereof opposite said integral hinges thereof.

4. A flexible paperboard article carrier blank comprising hingedly connected side and end wall panels, a longitudinal partition panel integrally hinged by a transverse crease to an end of an end wall panel, a first cross partition element integrally hinged by a vertical crease to said partition panel, a panel element integrally hinged by a longitudinal crease to a bottom forming margin of said longitudinal partition panel and adapted to be folded inwardly and upwardly into side-by-side relation to the latter, and a second cross partition element integrally hinged by a transverse crease to an end margin of said panel element and separated by a cut from said bottom margin of said longitudinal partition panel, said first and second cross partition panel elements being adapted to be hingedly secured to a side wall at the ends thereof opposite said integral hinges thereof.

5. An article carrier fabricated from flexible paperboard stock and comprising opposed pairs of side and end walls, a bottom extending between said side walls, a longitudinal partition

disposed medially between said side walls and hinged to one of said end walls, said partition comprising a longitudinally extending panel having a cross partition element connected thereto 5 on an integral vertical hinge, which partition element is hingedly secured to a side wall, and a further cross partition unit integrally hinged to the bottom margin of the longitudinal partition panel, said further cross partition unit including a panel element folded upwardly about said bottom hinge to said longitudinal partition panel and disposed in face to face relation thereto, and a cross partition panel integrally hinged at one end by a vertical crease to said upwardly folded panel element and hingedly secured at its opposite end to said side wall, said last named cross partition panel being separated by a cut from said bottom margin of said longitudinal partition panel.

6. An article carrier fabricated from flexible paperboard stock and comprising opposed pairs of side and end walls, a bottom extending between said side walls, a longitudinal partition disposed medially between said side walls and hinged to one of said end walls, said partition comprising a longitudinally extending panel having a cross partition element connected thereto on an integral vertical hinge, which partition element is hingedly secured to a side wall, and a further cross partition unit integrally hinged to a longitudinal margin of the longitudinal partition panel, said further cross partition unit including a panel element folded about said hinge relative to said longitudinal partition panel and disposed in face to face relation thereto, and a cross partition panel integrally hinged at one end by a vertical crease to said folded panel element and hingedly secured at its opposite end to said side wall, said last named cross partition panel being separated by a cut from the margin of said longitudinal partition panel to which said cross partition is hinged.

EDWIN L. ARNESON.
